FRITZ W. MEYER, OF JOHNSTOWN, PENNSYLVANIA, ASSIGNOR TO ROBERT S. WALTERS,
OF SOUTHMONT, PENNSYLVANIA

MANUFACTURE OF ELONGATED TUBULAR ARTICLES

Application filed February 23, 1929. Serial No. 341,878.

This invention relates to the manufacture of elongated tubular articles of cast metal, and is particularly applicable to the manufacture of cast iron pipes.

Cast iron pipes have heretofore been successfully made by centrifugal casting and by molding in sand molds, the molds being vertical, horizontal and sometimes inclined, but both of these processes are relatively expensive, especially in the manufacture of pipes of small diameter.

According to the present invention, there is provided a method and apparatus for the manufacture of cast metal pipes or the like which is relatively more simple and less expensive than present methods, and wherein a more uniform wall thickness is secured in the pipe. The invention is, furthermore, adapted to the forming of a plurality of pipes in a single mold at a single operation.

The invention may be readily understood by reference to the accompanying drawings which illustrate more or less generally the present invention, and in which

Figure 1 is a face view of one of the mold sections of the divided permanent mold used in the process;

Figure 2 is a transverse horizontal section through the mold in substantially the plane of line II—II of Figure 1;

Figure 3 is a similar section in substantially the plane of line III—III of Figure 1;

Figure 4 is a front view of the core;

Figure 5 is an enlarged cross section through the core carrier;

Figure 6 is a view similar to Figure 1 showing the core in place in the mold section; and

Figure 7 is an enlarged cross section through the mold and core in substantially the plane of line VII—VII of Figure 6.

According to the present invention, the tubular articles or lengths of pipe are formed in a permanent mold comprised of two complementary sections 2 and 2'. In each section are a plurality of vertically extending semi-circular mold cavities 3, the cavities being correspondingly disposed in the two sections, so that when the sections

are mated, there are a plurality of hollow mold cavities of circular cross section. Extending across the tops of the cavities 3 is a recess 4 in each of the mold sections to receive a horizontal core carrier. Rigidly carried on one of the mold sections and projecting from the face of the section in the recess 4 is a pin 5 which is preferably of non-circular cross section, and which is preferably triangular in cross section with the apex of the triangle in the vertical center line of the mold.

Formed at the bottom of the mold cavities are core supports 6, each of these supports 6 having a central socket 7 therein adapted to receive the bottom end of a core. At each side of the core support 6 for each mold cavity is a gate 8 through which the molten metal may flow from a passage 9 in the bottom of the mold into each of the individual mold cavities. The passage 9 communicates with a main metal inlet gate 10 at the bottom of the mold.

In the particular construction shown in the drawings, there are three mold cavities 3, but this number can be varied according to the size of the mold sections and the diameters of the pipes to be formed. Each mold, however, preferably provides more than a single mold cavity.

Centrally positioned in each mold cavity 3 is a coaxially extending core 11. The lower ends of the cores 11 are received in the sockets 7 in the supporting members 6 at the bottoms of the mold cavities while the upper ends of the cores are connected with an integral core carrier in the form of a cross piece 12, which cross piece 12 is adapted to be received in the cavity 4 in the upper part of the permanent mold. The core carrier 12 is preferably reinforced by an embedded strip of metal 13. In the center of this strip of metal, and passing transversely through the core carrier is a hole 14 through which the pin 5 of the mold can pass. The opening 14 is preferably triangular in cross section and is larger than the pin 5 so that the core carrier can adjust itself with respect to the mold.

In practice, the core carrier with the de-

pendent cores 11 is placed in one of the mold sections with the pin 5 passing through the opening 14. The triangular pin engaging in the triangular opening provides a single point suspension for the core carried and its dependent cores. The lower ends of the cores project into the sockets 7 of the core supports 6 at the bottoms of the mold cavities.

By reason of the cores being firmly supported at their lower ends and being rigidly connected with the core carrier 12 at their upper ends, they are properly centered in the mold cavities 3, and chaplets do not have to be used to retain the core in place. The elimination of chaplets in the process of casting the pipe is of considerable importance.

The cores 11 are molded from silica sand with which has been mixed a bonding or a temporary bonding material, such as oil or corn syrup, as will be readily understood by those skilled in foundry practice. The molded silica cores are fired to develop the necessary strength in the molded material, the molding of the cores and the core carriers being done in accordance with present methods, as will be readily understood by those skilled in the art.

As will be understood by those skilled in the art, the cores are formed in a divided core box, half of the core structure being molded in one section of the box and half being molded in the other section of the box. The two sections are then put together to form the complete core, after which one section of the box is removed and the other section is utilized to support the molded core while it is being fired.

However, before the two halves of the core are put together, a shallow groove is formed along the center of each of the cores, this groove communicating with a cross groove in the core carrier and leading to a vent opening so that there is a vent passage 15 in each of the cores 11. This vent passage communicates with the vent passage extending crosswise in the carrier 4, the gases escaping through a vent at 15'. Air escape passages are indicated at 15a.

After the cores and the core carrier have been placed in one of the mold sections 2, the other mold section is closed over the first, and the mold is then brought into position over a pressure casting unit which is diagrammatically indicated at A. This pressure casting unit may be of any well known or preferred type, and after the mold has been positioned over it, molten metal is forced into the passage 10' from which it flows along the passage 9 and through the gates 8 to the respective mold cavities. Due to the fact that there are oppositely disposed gates for each mold cavity, the cores are not pushed to one side or the other by the force of the incoming metal, and an even wall thickness is

maintained. As the mold cavities are filled with metal, the gases permeate the cores, escaping through the vent passages provided in the cores.

The permanent molds can be cooled in any suitable or preferred manner, as will be understood by those skilled in the art. After the castings have become cold, they are removed from the mold and the core material is cleaned out.

It will be noted that I preferably employ cores which are self-sustaining and require no arbor either for reinforcing the core or for removing gases. This is of considerable advantage because in processes of casting pipes as heretofore carried out wherein a sand core is used, the nature of the core has been such as to require the use of an arbor. Due to temperature changes, the arbors which have been used have been found to warp and become distorted, producing tubes of uneven wall thickness and non-uniform character. Obviously, however, in carrying out the present invention, arbors may be used in the cores where it is desired to do so.

According to the present invention, therefore, it is necessary to use neither chaplets nor arbors in the cores. The manner of mounting the core system, comprising the cores and the core carrier, in one section of the mold allows the core system to be set in place without pulling or straining the cores.

The apparatus is relatively simple. It will be understood that in the accompanying drawings the structure of the permanent molds has only been outlined in a general way, and can be modified and changed in various ways to provide for the closing of the mold and to provide for the cooling thereof. It will be understood that the number of mold cavities may be varied according to the diameter of the pipe being cast, and that where pipe other than pipe having a circular cross section is to be cast, the shape of the mold cavities can be correspondingly modified. In practicing the invention, the tube lengths which are cast will ordinarily exceed four feet, preferably being about six feet. Various modifications and changes may be made within the spirit of the invention and under the scope of the following claims:

I claim:

1. The method of forming cast metal tubes which comprises introducing metal into the bottom of an elongated vertical mold cavity about a core which is supported only at the opposite ends of the cavity, the metal being simultaneously introduced into the mold cavity at opposite sides of the center line of the core.

2. Apparatus for the manufacture of cast metal tubes comprising a permanent mold formed of two vertical sections and in which

is provided a vertically extending elongated mold cavity, means at the bottom of the cavity for receiving and supporting a core at the center of the cavity, means at the top of the mold for supporting the top of a core, a core in the cavity carried by the supporting means, and means for introducing metal into the mold cavity at the bottom thereof.

3. Apparatus for the manufacture of cast metal tubes comprising a permanent mold formed of two vertical sections and in which is provided a vertically extending elongated mold cavity, means at the bottom of the cavity for supporting a core at the center of the cavity, means at the top of the mold for supporting the top of a core, a core in the cavity carried by the supporting means, and means for introducing metal into the lower end of the core cavity at opposite sides of the core.

20 4. Apparatus for the manufacture of cast metal tubes comprising a permanent mold formed of two vertical sections and in which is provided a vertically extending elongated mold cavity, means at the bottom of the cavity for supporting a core at the center of the cavity, means at the top of the mold for supporting the top of a core in a central position and closing the top of the mold cavity, a core in the cavity carried by the supporting means, said core comprising a self-sustaining mass of bonded silica sand.

25 5. Apparatus for the manufacture of cast metal tubes comprising a permanent mold formed of two vertical sections, said mold having a plurality of vertically extending mold cavities therein, a core support at the bottom of each cavity, a core carrier in the mold above the vertical cavities, a plurality of cores on the carrier, one of which is centrally positioned in each cavity and has its lower end received in the core support at the bottom of the cavity, and means for introducing molten metal into the bottom of the respective cavities.

30 6. Apparatus for the manufacture of cast metal tubes comprising a permanent mold formed of two vertical sections, said mold having a plurality of vertically extending mold cavities therein, a core support at the bottom of each cavity, a core carrier in the mold above the vertical cavities, a plurality of cores on the carrier, one of which is centrally positioned in each cavity and has its lower end received in the core support at the bottom of the cavity, whereby the core in each cavity is supported only adjacent its ends, and means for introducing metal into the lower end of each cavity.

35 7. Apparatus for the manufacture of cast metal tubes comprising a permanent mold formed of two vertical sections, said mold having a plurality of vertically extending mold cavities therein, a core support at the bottom of each cavity, a core carrier in the mold above the vertical cavities and closing

the tops of the vertical mold cavities, a plurality of cores on the carrier, one of which is centrally positioned in each cavity and has its lower end received in the core support at the bottom of the cavity, whereby the core in each cavity is supported only adjacent its ends, and means for introducing metal into the lower end of each cavity at opposite sides of the core.

8. Apparatus for the manufacture of cast metal tubes comprising a core system having a carrier with a plurality of depending core members, said core system being formed of bonded silica sand, and a divided permanent mold having vertical mold cavities adapted to receive the core system, said mold having core supporting means at the bottom of each cavity, the cores being supported in the mold only at the bottom of the cavity and adjacent the mold carrier, the core carriers being positioned out of the mold cavities.

9. Apparatus for the manufacture of cast metal tubes comprising a core system comprised of a reinforced core carrier from which depend a plurality of self-sustaining bonded silica sand cores, a permanent mold comprised of two vertical sections, said permanent mold having a plurality of vertically extending elongated mold cavities therein along which the cores extend, means at the top of the mold for receiving the core carrier, and means at the bottom of each cavity for receiving and supporting the lower ends of the cores, the core carriers being positioned out of the mold cavities.

10. Apparatus for the manufacture of cast metal tubes comprising a core system comprised of a reinforced core carrier from which depend a plurality of self-sustaining bonded silica sand cores, a permanent mold comprised of two vertical sections, said permanent mold having a plurality of vertically extending elongated mold cavities therein along which the cores extend, means at the top of the mold for receiving the core carrier, means at the bottom of each cavity for receiving and supporting the lower ends of the cores, and means for introducing molten metal into the bottom of each mold cavity.

11. Apparatus for the manufacture of cast metal tubes comprising a mold system having a core carrier and a plurality of cores depending from the carrier, said cores being formed of bonded silica sand permeable to gases, the cores having a central gas escape passageway therealong, a divided permanent mold for cooperation with the core system having vertical mold cavities therein with means at the bottom of each cavity for receiving and supporting the core, and means in the top of the mold for receiving and supporting the core carrier.

12. Apparatus for the manufacture of cast metal tubes comprising a mold system having a core carrier and a plurality of cores de-

pending from the carrier, said cores being formed of bonded silica sand permeable to gases, the cores having a central gas escape passageway therealong, a divided permanent mold for cooperation with the core system having vertical mold cavities therein with means at the bottom of each cavity for receiving and supporting the core, means in the top of the mold for receiving and supporting the core carrier, and means for forcing metal under pressure into the mold cavities adjacent the bottoms of the mold cavities.

13. Apparatus for the manufacture of cast metal tubes comprising a core system having a core carrier from which depend a plurality of self-sustaining silica sand cores, said core carrier having a transverse opening therethrough and a divided permanent mold for cooperation with the core system comprised of two sections, said mold having a plurality of vertically extending mold cavities therein along which the cores extend, a pin on one of the permanent mold sections passing through said opening in the core carrier and providing a single point suspension for said carrier.

14. Apparatus for the manufacture of cast metal tubes comprising a core system having a core carrier from which depend a plurality of self-sustaining silica sand cores, said core carrier having a transverse opening therethrough, a divided permanent mold for cooperation with the core system comprised of two sections, said mold having a plurality of vertically extending mold cavities therein along which the cores extend, a pin on one of the permanent mold sections passing through said opening in the core carrier and providing a single point suspension for said carrier, and means at the bottom of each mold cavity for receiving and supporting the end of a core.

15. Apparatus for the manufacture of cast metal tubes comprising a core system having a core carrier from which depend a plurality of self-sustaining silica sand cores, said core carrier having a transverse opening therethrough, a divided permanent mold for cooperation with the core system comprised of two sections, said mold having a plurality of vertically extending mold cavities therein along which the cores extend, a pin on one of the permanent mold sections passing through said opening in the core carrier and providing a single point suspension for said carrier, and means at the bottom of each mold cavity for receiving and supporting the end of a core, said opening through the core carrier being triangular in cross section, said pin also being triangular in cross section, the pin being of smaller cross section than the opening, the apex of the pin and the apex of the opening coinciding with the vertical center line of the mold.

16. Apparatus for the manufacture of cast metal tubes comprising a permanent mold formed of two vertical sections, said mold having a plurality of vertically extending elongated mold cavities therein, a core support at the bottom of each cavity, means in the top of the mold for receiving and supporting a core carrier, and means for introducing metal under pressure into the bottoms of each of the mold cavities.

In testimony whereof I have hereunto set my hand.

CERTIFICATE OF CORRECTION.

Patent No. 1,790,108.

Granted January 27, 1931, to

FRITZ W. MEYER.

It is hereby certified that the name of the assignee in the above numbered patent was erroneously written and printed as "Robert S. Waiters", whereas said name should have been written and printed as Robert S. Waters, as shown by the records of assignments in the office; and that the said Letters Patent should be read with this correction therein that the same may conform to the record of the case in the Patent Office.

Signed and sealed this 24th day of February, A. D. 1931.

(Seal)

**M. J. Moore,
Acting Commissioner of Patents.**
